Primary Examiner — Kendra Leslie Hamilton(74) **Attorney, Agent, or Firm** — Rankin, Hill & Clark LLP(57) **CLAIM**

The ornamental design for a bottle lid, as shown, and described.

DESCRIPTION

FIG. 1 is a top, front, left perspective view of a bottle lid showing our new design;

FIG. 2 is a left side view thereof;

FIG. 3 is a front elevation view thereof;

FIG. 4 is a top plan view thereof;

FIG. 5 is a bottom plan view thereof; and,

FIG. 6 is a top, front, left perspective view of the bottle lid of FIG. 1, shown in a condition of use.

The broken lines in FIG. 5 illustrate portions of the bottle lid that form no part of the claimed design. The broken lines in FIG. 6 showing a bottle illustrate environmental subject matter only and form no part of the claimed design.
